CLAIM

The ornamental design for a watch band, as shown and described.

DESCRIPTION

FIG. 1 is a rear perspective view of a watch band according to a first embodiment of my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof;

FIG. 10 is an enlarged view of encircled portion 10 of FIG. 9;

FIG. 11 is a rear perspective view of a watch band according to a second embodiment of my new design;

FIG. 12 is a front perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an exploded view thereof; and,

FIG. 20 is an enlarged view of encircled portion 20 of FIG. 19.

The evenly broken lines shown in the drawings are included for the purpose of illustrating parts of the article. The dot-dash broken lines represent the designation of enlargement views. None of the broken lines form part of the claimed design.

1 Claim, 20 Drawing Sheets
